UNITED STATES PATENT OFFICE

2,418,329

SWITCH

Carl E. Bazley, Schenectady, N. Y., assignor to
General Electric Company, a corporation of
New York

Application August 28, 1944, Serial No. 551,484

3 Claims. (Cl. 200—165)

1

My invention relates to switches, more particularly to electromagnetically operated switches, and has for its object a simple and reliable shockproof switch.

In carrying out my invention in one form, I provide two spring contact arms which are mounted so as to extend in substantially parallel relation with each other and which are provided with contacts on their ends normally in engagement with each other. For controlling the engagement and disengagement of the contacts, I provide a slider member made of electrically insulating material having a slot or aperture providing side walls between which the two spring arms extend. When the slider member is moved to one extreme position, the side walls of the slot engage opposite sides of the spring arms whereby the spring arms are secured with the contacts in engagement with each other. Movement of the slider in the opposite direction to an extreme position brings a projecting separating member between the spring arms whereby they are forced apart and each held securely between walls of separate relatively narrow slots.

For a more complete understanding of my invention, reference should be had to the accompanying drawing, Fig. 1 of which is a side elevation view of an electromagnetically operated switch embodying my invention; Fig. 2 is a front elevation view of the device shown in Fig. 1; Fig. 3 is a sectional view taken along the line 3—3 of Fig. 2; while Fig. 4 is a view similar to Fig. 3 but showing the switch in its open circuit position.

Referring to the drawing, in one form of my invention I provide a slider member 1 in the form of a plate and made from a rigid electrically insulating material such as a suitable hard fibre. This plate is mounted for limited sliding movement on two supporting bars 2 and 3, secured to an electrically insulating supporting member 4 which, in turn, is secured to a metal supporting bracket 5. Thus the supports 2 and 3 are cut away at their outer ends, or left-hand ends as viewed in Fig. 1, to form a shallow depression for the plate 1, as shown clearly in Fig. 4, the plate being slidably secured in place by cross bars 6 and 7.

The plate or slider member 1 is provided in the form shown with three slots or apertures 8, 9 and 10 through which extend respectively

2

pairs 11, 12 and 13 of spring contact members or arms secured to the insulating support 4 by means of suitable screws, as shown in Figs. 3 and 4. The contact arms extend, as seen in Fig. 3, in substantially perpendicular relation to the support 4 and in parallel relation with each other, these positions being the normal biased positions of the arms. On its outer movable end each contact arm is provided with an electric switch contact on the side adjacent the other arm of the pair so that when the arms are substantially parallel, the contacts of each pair are in engagement with each other. As shown in Fig. 3, the pairs of contacts 14 and 15 are in engagement with each other.

With the plate 1 in its uppermost position, as shown in Figs. 2 and 3, the pairs of spring contact arms 11 and 12 extend through the lowermost relatively wide portions of the slots 8 and 9 whereby the opposite side walls of each slot engage the spring arms and secure them in their closely spaced parallel relation, as shown, with their contacts in engagement with each other. Also in this position of the plate 1, the lowermost pair of contacts 13 are separated by a pointed projection member 16 on the plate 1 which is positioned between them, the two contact arms then extending in widely spaced relation each through a relatively narrow slot, these slots 17 and 18 being separated by the projection 16.

When the plate 1 is moved downward from the position shown in Fig. 2, the pointed separating projection members 19 and 20 move respectively between and separate the pairs of arms 11 and 12 thereby separating their contacts, as shown in Fig. 4. Each arm of the pairs 11 and 12 then extends through separate relatively narrow slots on opposite sides of the projections 19 and 20.

At the same time, when the plate was moved downward, the pair of contacts 13 moved into the uppermost portion 21 of their slot 10 so as to be held together in closed circuit position by the side walls of this slot. As the plate is moved downward, the spring arms 13 are engaged by the obliquely extending side walls 22 and 23 and are thereby guided into the upper portion 21 of the slot, providing such guiding is required. This guiding by the walls 22 and 23 might be required, for example, if the contact arms are initially bent or deformed so as to be biased

apart to their open circuit positions, as shown in Fig. 2.

It will be observed that the rigid side walls of the relatively wide slots and the two relatively narrow slots associated with each pair of spring contact arms are parallel with the direction of the reciprocating movements of the plate 1, whereas the spring contact arms are spaced apart on the supporting member 4 in a direction substantially transverse with respect to the movement of the plate 1. Therefore, the walls of the slots are parallel with the sides of the spring arms and secure the spring arms rigidly in their closed and open circuit positions. Moreover, it will be observed that the two relatively narrow slots are connected with the relatively wide slot by means of two slots converging toward each other, thereby to form the pointed projection 16.

For the purpose of limiting the upward and downward movement of the plate 1, the plate is provided on its opposite sides with projections 24 and 25 which engage the supports 2 and 3 in the extreme positions of the plate.

It will be observed that the contact arms of each pair are held securely by the walls of the slot through which they extend in both their open circuit and closed circuit positions whereby false operation of the contacts by heavy impact shocks is prevented. In other words, the spring arms are held securely in both their open circuit and closed circuit positions.

For the operation of the plate 1, I have shown an electromagnet comprising a coil 26 provided with a plunger armature 27, the coil being mounted on the bracket 5 and additionally supported by a bracket 28 having one end secured to the upper end of the bracket 5. The plunger armature 27 is connected through a pivot 29 to a lever arm 30 having an intermediate pivot 31, and its left-hand end connected through a pivot 32 and bracket 33 to the plate 1. The armature 27 is biased to its lowermost unattracted position, as shown in Fig. 1, by means of a helical spring 34 surrounding the armature. For movement of the plate 1 downward, the coil is energized. Sufficient looseness is provided between the plate 1 and its supporting guides 2 and 3 to provide for the small lateral movement of the plate in moving about the pivot 31.

In the particular embodiment shown in the drawing, the two pairs of contact arms 11 and 12, as shown in Figs. 3 and 4, are connected electrically in series with each other, the two pairs being connected in a circuit to be controlled by means of suitable binding posts 35 and 36. Similar binding posts 37 and 38 are provided for the pair of arms 13. I contemplate that the two pairs of contact arms 11 and 12 will be connected in an energizing circuit for the coil 26 together with, for example, a push button, while the pair 13 is connected in a holding circuit for the coil 26. Thus, when the coil is energized through the contact arms 11 and 12, the magnet picks up its armature and thereby moves the plate 1 downward. As the plate moves downward, the pair of arms 13 are moved to bring their contacts into engagement with each other thereby to close the holding circuit for the coil before the separating members 19 and 20 engage and separate the arms 11 and 12. Further downward movement of the plate separates the contact arms 11 and 12.

While I have shown a particular embodiment of my invention, it will be understood, of course, that I do not wish to be limited thereto since

many modifications may be made, and I therefore contemplate by the appended claims to cover any such modifications as fall within the true spirit and scope of my invention.

5 What I claim as new and desire to secure by Letters Patent of the United States is:

1. A shockproof switch comprising a support, a member made of electrically insulating material slidably mounted on said support and having an aperture provided with a first portion having opposite side walls substantially parallel with the direction of movement of said member, a pointed projection on a side wall of said aperture opposite said first portion dividing said aperture into two narrow portions, each having parallel side walls extending in the direction of movement of said member, opposite side walls for said aperture joining said first portion with said narrow portions extending obliquely with respect to the direction of movement of said member, and two switch arms extending through said aperture secured in closely spaced relation with respect to each other by said parallel side walls of said first portion when said member is in a first predetermined position, said switch arms when said member is moved to a second predetermined position being separated by said projection and secured in said narrow aperture portions, and said switch arms when said member is moved from said second position to said first position being guided by said obliquely extending side walls into said first aperture portion.

2. A shockproof switch comprising a support, a plate member made of rigid electrically insulating material, means slidably mounting said plate member on said support for reciprocating movement, said plate member being provided with one relatively wide slot having rigid parallel side walls extending in the direction of movement of said plate member and with two relatively narrow slots having rigid side walls substantially parallel with the direction of movement of said plate member and said plate member being provided with converging slots joining said relatively narrow slots with said relatively wide slot thereby to form a projection opposite said relatively wide slot, a pair of spring contact arms secured in spaced relation with each other to said support and extending through said relatively wide slot when said plate member is in a first predetermined position, and switch contacts on said spring arms secured in closed circuit contact engaging relation with each other by the rigid side walls of said relatively wide slot, said spring arms when said plate member is moved to a second predetermined position moving into said relatively narrow slots into contact disengaged relation and being secured each between the rigid side walls of its relatively narrow slot.

3. A switch comprising a support, an operating member made of rigid material, means slidably mounting said operating member on said support for movement back and forth in a predetermined path, said operating member being provided with at least one aperture extending along said path, a pair of switch arms secured to said support and extending through said aperture, said aperture being provided at one end with a relatively wide portion having side walls substantially parallel with said path and at its opposite end with two spaced apart relatively narrow aperture portions having each side walls extending substantially parallel with said path, said narrow aperture portions being connected with said relatively wide aperture portion by converging aperture portions,

and means for moving said operating member in one direction to one position in which said switch arms extend through said relatively wide portion so as to be secured by its side walls in closely spaced relation with each other and for moving said operating member in the opposite direction to a second position in which said switch arms extend respectively through said relatively narrow aperture portions so as to be secured by the side walls thereof in a predetermined widely spaced relation with each other.
